UNITED STATES PATENT OFFICE.

CHARLES E. POPE, OF HOLYOKE, MASSACHUSETTS.

PAPER-MAKING MACHINE

1,197,656.

Specification of Letters Patent. Patented Sept. 12, 1916.

Application filed August 25, 1913. Serial No. 786,462.

To all whom it may concern:

Be it known that I, CHARLES E. POPE, a citizen of the United States, residing in Holyoke, in the county of Hampden, in the State of Massachusetts, have invented certain new and useful Improvements in Paper-Making Machines, of which the following is a specification.

This invention relates to paper making machines and more particularly to means for picking a layer of pulp from the making wire of a paper machine in an improved manner. It finds one of its best adaptations in connection with a Fourdrinier machine in which, the pulp is formed on a wire which travels continuously in the paper making operation.

The accompanying figure illustrates diagrammatically a portion of a Fourdrinier machine which is directly involved in the application of my invention.

Referring to this figure, the frame carrying the wet end of the machine is designated *r* and the frame carrying the felts is designated *s*. A portion of the making wire *b* of the machine is shown as it passes over suction box *c*, guide rolls *d*, and between the couch rolls *e* and *f*. The layer or sheet of pulp *a* shown by dotted line is carried by the wire *b*, as shown. The felt *k* passes around the upper couch roll *e* and meets the layer of pulp held on the wire as the latter passes between the couch rolls. Instead of the making wire passing around the lower couch roll *f* as has heretofore been the practice, it passes around a supplemental guide roll *h*, suitably mounted in frame *s*. Roll *h* is located beyond the couch rolls, that is, it is spaced from the couch rolls in the direction of travel of the making wire. This arrangement is of particular importance in a high speed machine since all the sharp turns, which must usually be taken by the paper web while in a weak condition, are eliminated. Between the couch roll *f* and the supplemental guide roll *h* I place a suction box *y* (shown in cross section). The felt *k* guided by the under surface of the suction box travels at an angle away from the wire *b* and meets the lower felt *w* guided by rolls *m* in a manner shown in the drawing. It will be noticed that where the felt and the sheet of pulp leave the wire, the un-

der surface of the latter does not bear against the couch roll or any other surface which would hold the ends of the fibers clenched to the wire. These fibers are, therefore, free to be taken away from the wire with very little force. The suction box bearing on a given area of the upper side of the felt acts through the latter to draw the sheet away from the wire. This structure and arrangement permits a sufficient pressure to act through the wire to transfer the sheet readily to the felt. This, I believe, to be broadly new.

In the ordinary operation of the Fourdrinier machine the making wire together with a sheet of pulp passes between couch rolls which press the sheet of pulp before it is transferred to what is called the pick up felt. The wire, according to present practice, passes around the lower of the two couch rolls before beginning its backward travel, the felt ordinarily passes around the upper couch roll and comes in contact with the sheet of pulp on the wire, causing the said sheet to be picked off by the felt and carried away from the wire. In manufacturing some papers, there is considerable difficulty in getting the sheet of pulp away from the wire and on to the surface of the felt. In analyzing the difficulties involved, I have found that the fiber forming the pulp sheet, passes through the small meshes of the making wire and extends from the underside thereof, so that when the wire passes around the lower couch roll these downwardly hanging ends of the fibers are clenched and held to the wire. When the felt tends to pick the layer of pulp away from the making wire these fibers, being clenched to the wire and held clenched by the surface of the lower couch roll, tend to prevent the desired transfer. For a long time paper makers have known that the difficulty exists, but, there has not, as far as I know been an adequate explanation of the difficulty as I have explained it. If the paper being made is heavy enough it will have sufficient strength to be pulled away from the wire in spite of the clenched fibers. On the other hand if it is light enough the strength of the clenched fibers will not be sufficient to prevent its ready transfer to the felt. But between these two conditions there

are many weight papers desired where the clenched fibers are strong enough to prevent the proper transfer of the sheet of pulp from the wire at a point where the latter is in contact with the roll. In order to obviate this difficulty it has been customary in the past to groove the lower couch roll or to perforate this roll. By this means there is a smaller area of the wire in actual contact 10 with the couch roll, than if the latter were not grooved or perforated. This results in the felt picking the paper off the wire because of the decreased holding area of the clenched fibers as the wire passes around the 15 grooved roll. There are many disadvantages in either grooving the roll or perforating it besides the expense involved. For example, it is well known that the two couch rolls are pressed toward one another with considerable force and this pressure on the making wire which passes between the rolls, causes the wire to be pushed into the grooves or perforations, thus shortening its life. By the use of my invention the life of the wire 20 is much longer than has heretofore been the case.

I provide means for picking the sheet of pulp at a point where the underside of the wire is not in contact with any roll, either 25 grooved or perforated, but on the contrary is exposed, so that as the layer of pulp leaves the wire the ends of the fibers which are ordinarily held clenched by the roll, are free to be pulled through the meshes of the wire 30 with a small amount of force. The suction box if acting on a given area of the sheet through the felt will make the desired transfer to the felt without the possibility of damage. It will thus be seen that by my invention the roll, instead of being grooved or 35 perforated can be smooth and that the pulp layer will be transferred to the felt in an improved manner.

It will be understood that the machine 40 illustrated in the drawings is intended to illustrate a portion of the Fourdrinier machine with the parts operating as usual, except for improved adaptations of the machine as specifically described. I realize that 45 many different adaptations of my invention might be made to the Fourdrinier and other machines and I have, therefore, illustrated and described the specific adaptation for 50 illustrative purposes only.

55 What I claim is:—

1. A paper making machine having in combination a movable making wire, couch rolls between which the wire and pulp sheet thereon pass together with means located beyond the couch rolls for guiding the wire, a felt arranged to pick the pulp sheet from the wire between the couch rolls and the guiding means and a stationary suction box above the felt to insure the transfer of 60 the pulp sheet to the felt.

2. A paper making machine having in combination, a movable making wire, couch rolls between which the wire and sheet thereon pass together with means located beyond the couch rolls for guiding the wire, a felt 70 arranged to pick off the sheet from the wire between the couch rolls and the guiding means, and means to create a pneumatic pressure acting through the wire toward the felt whereby the transfer of the pulp sheet 75 to the felt is insured.

3. A paper making machine, having in combination, a movable making wire, a felt suitably mounted in the machine, couch rolls between which the wire and the felt 80 pass with the pulp sheet therebetween, means for guiding the wire beyond the couch rolls, and means constructed and arranged to guide the felt and sheet away from the wire between the couch rolls and said guiding 85 means including a device to cause a pneumatic pressure acting through the wire toward the felt as the latter leaves the wire.

4. A paper making machine having in combination, a movable making wire, couch 90 rolls between which the wire and sheet thereon pass, a felt, means for pressing the felt against the sheet on the wire at a point beyond the couch rolls where the underside 95 of the wire is exposed, and thereafter separating the felt and sheet carried thereby from the wire at such a point, said means including a device for causing a pneumatic pressure acting through the wire toward the 100 felt.

5. A paper making machine, having in combination, a movable making wire, a felt suitably mounted in the machine, couch rolls between which the wire and felt pass with the pulp sheet therebetween, a guide 105 roll located beyond the couch roll around which the wire travels, means located between the couch rolls and the first mentioned guide roll for directing the felt with the sheet thereon away from the wire including 110 a device for causing a pneumatic pressure acting through the wire toward the felt.

6. A paper making machine having in combination, a movable endless making wire, guiding means therefor including a couch 115 roll and a guide roll located beyond the couch roll around which the wire turns from its upper to its lower travel, an upper couch roll, a movable endless felt passing around the upper couch roll and into contact with the pulp sheet carried by the wire, means located between the couch roll and the guide roll to press the felt against the pulp sheet and to guide the latter and the felt away from the wire at a point where the 120 underside of the wire is exposed including a device for causing a pneumatic pressure on the underside of the wire toward the felt.

7. A paper making machine comprising in combination, a making wire, couch rolls, an 130

upper felt carried around the upper couch roll, means to guide the wire and felt with the pulp sheet therebetween beyond the couch rolls, and means to separate the felt with the pulp sheet adhering on the underside thereof from the wire at a point where the underside of the latter is exposed, in-

cluding a device for causing a pneumatic pressure acting through the wire toward the felt at the point of separation.
